(57) **CLAIM**

The ornamental design for a handle of terminal block as shown and described.

DESCRIPTION

FIG. 1 is a first perspective view of a handle of terminal block showing my new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is second perspective view showing the handle of terminal block.

FIG. 9 is third perspective view showing the handle of terminal block; and,

FIG. 10 is a perspective view showing the handle of terminal block in use.

The dot-dash lines in the Figures are reference lines that form no part of the claimed design.

The broken lines shown in the figures form no part of the claimed design. The dot-dash broken lines represent a boundary line between claimed and unclaimed surfaces. The dash-dash broken lines shown in FIGS. 1-9 represent unclaimed portions of the handle of a terminal block. The remaining dash-dash broken lines shown in FIG. 10 represent environment.
